UNITED STATES PATENT OFFICE.

CHARLES A. WINTER, OF NEW YORK, N. Y.

MOTOR ATTACHMENT FOR WRINGERS.

Application filed June 8, 1920. Serial No. 387,324.

To all whom it may concern:

Be it known that I, CHARLES A. WINTER, a citizen of the United States, and a resident of the city of New York, borough of Manhattan, in the county and State of New York, have invented a new and Improved Motor Attachment for Wringer, of which the following is a full, clear, and exact description.

10 This invention relates to attachments for wringing machines, and has for an object to provide an improved arrangement whereby the power motor may be connected to a wringer of any usual or preferred type without changing the wringer.

Another object of the invention is to provide a motor attachment for a wringer which may be quickly applied and removed, arrangements being such that the wringer may 20 be quickly converted into a power wringer or into a hand operated wringer.

A still further object of the invention is to provide a power member adapted to be connected with a wringer and constructed 25 to provide a reversing action for the wringer which may be easily manipulated for causing the wringer to act in substantially the same manner as if hand driven, though with more speed, and in both directions.

30 In the accompanying drawing—

Figure 1 is a front view of a wringer of an ordinary type with an attachment embodying the invention applied thereto.

Fig. 2 is a side view of the construction 35 shown in Fig. 1.

Fig. 3 is a side view of the arrangement shown in Fig. 1, the same being on the opposite side to that shown in Fig. 2.

Fig. 4 is a top plan view of the structure shown in Fig. 1.

Fig. 5 is a fragmentary front view showing the adjustable mounting for the power member disclosed in Fig. 1.

Referring to the accompanying drawings 45 by numerals, 1 indicates a wringer which is provided with a frame 2 and a set of rollers 3. The rollers 3 are provided with intermeshing gears in the usual manner, and one roller is provided with a crank shaft 4 having the usual nut 5 on the end. When operated by hand a suitable crank is arranged on shaft 4 and the rollers 3 rotated thereby. When using the power motor 6 for rotating the rollers 3, the crank 4 is removed and a 55 comparatively large gear wheel 7 secured on shaft 4 at or adjacent the point where the

crank was placed. The gear wheel 7 meshes continually with a comparatively small pinion 8 which is carried by shaft 9, said shaft in turn having a large pulley wheel 60 10 connected thereto on the opposite side of frame 2 so as to accommodate the belt 11, which belt passes over a small pulley 12 connected to the rotor of the motor 6. The shaft 9 is carried in suitable bearing blocks 65 connected to frame 2 by brackets 13, which brackets are bolted, screwed or otherwise secured to said frame. When power is used the parts are connected as shown in Fig. 1, but if for any reason it be desired not to use power 70 belt 11 is thrown off of the pulley 10 and the crank is connected with shaft 4 whereupon the roller 3 may be manipulated manually.

In order to quickly apply or remove the 75 motor 6 the same is mounted on a base 14 hinged at 15 to an auxiliary base 16. The auxiliary base 16 has a number of supporting posts 17 rigidly secured thereto, said supporting posts being preferably tapered 80 at their lower ends for fitting snugly into the various socket members 18 secured to frame 2. When the belt 11 has been thrown off of pulley 10 the supporting posts 17 may be readily pulled out of the sockets, base 16, 85 motor 6 and associated parts may be quickly removed and placed to one side. With regard to base 14 and the auxiliary base 16 it will be observed from Figure 5 that this arrangement permits a slight adjustment 90 vertically of the motor 6 so as to produce a proper tension in belt 11. This adjustment is permitted by the hinge 15 and caused by the set screw 19 which may be adjusted to any desired position. Current may be let 95 into the motor 6 in any desired manner, and a cut-off switch may be provided at any point. However, a reversing switch 20 is positioned on the base 14 and is provided with a handle 21 directly above the frame 2 100 so that a person using the wringer may operate switch 20 for causing the wringer to move in either direction or cut off the current.

I claim:

1. As a new article of manufacture, a portable motor support for a wringer, comprising a base, a platform hingedly secured to said base, said base having a plurality of legs extending therefrom and adapted to engage 110 sockets secured to said wringer, said motor having a pulley adapted to engage a belt

105

110

driving said wringer, and means associated with said base and acting against said platform to vary the tension of said belt.

2. As a new article of manufacture, a base, standards secured to said base and adapted to engage sockets on a support, a member mounted on said base adapted to support a motor having a pulley, said pulley being adapted to drive a belt, and means for forcing said member away from said base for bringing said belt under tension.

3. As a new article of manufacture, a

base, standards secured to said base and adapted to engage sockets on a support, a member mounted on said base adapted to support a motor having a pulley, said pulley being adapted to drive a belt, and means for forcing said member away from said base for bringing said belt under tension, together with a switch carried on said member for starting or changing the rotation of said motor.

CHARLES A. WINTER.
